(57) **CLAIM**

The ornamental design for a combined jewelry bracelet and pendant, as shown and described.

DESCRIPTION

FIG. 1 is a front elevational view of a first embodiment of a combined jewelry and bracelet pendant showing our new design;

FIG. 2 is a rear elevational view of FIG. 1;
FIG. 3 is a top plan view of FIG. 1, the bottom plan view being a mirror image thereof;

FIG. 4 is a right end view of FIG. 1, the left end view being a mirror image thereof;

FIG. 5 is a front elevational view of a second embodiment of a combined jewelry and bracelet pendant showing our new design;

FIG. 6 is a rear elevational view of FIG. 5;

FIG. 7 is a front elevational view of a third embodiment of a combined jewelry and bracelet pendant showing our new design;

FIG. 8 is a rear elevational view of FIG. 7;

FIG. 9 is a front elevational view of a fourth embodiment of a combined jewelry and bracelet pendant showing our new design;

FIG. 10 is a rear elevational view of FIG. 9;

FIG. 11 is a front elevational view of a fifth embodiment of a combined jewelry and bracelet pendant showing our new design;

FIG. 12 is a rear elevational view of FIG. 11;

FIG. 13 is a front elevational view of a sixth embodiment of a combined jewelry and bracelet pendant showing our new design;

FIG. 14 is a rear elevational view of FIG. 13;

FIG. 15 is a front elevational view of a seventh embodiment of a combined jewelry and bracelet pendant showing our new design;

FIG. 16 is a rear elevational view of FIG. 15;

FIG. 17 is a front elevational view of an eighth embodiment of a combined jewelry and bracelet pendant showing our new design; and

FIG. 18 is a rear elevational view of FIG. 17.

The bottom, top and end views of the second through the eighth embodiments are identical to those shown in FIGS. 3 and 4 of the first embodiment.

The side and end views of the second through the eighth embodiments are identical to those shown in FIGS. 4 and 5 of the first embodiment.
